CHILD'S STOOL

Haskell Benson, Chicago, Ill.

Application June 9, 1954, Serial No. 30,889

Term of patent 14 years

(Cl. D15—8)

Fig. 1 is a perspective view of a child's stool showing my new design as viewed from the front left and slightly above; and

Fig. 2 is a perspective view of the same but viewed from the right rear.

I claim:

The ornamental design for a child's stool, substantially as shown.
